SOLE-AFFIXING MACHINE

Arthur J. Weiss, West Orange, N. J., assignor to
 Compo Shoe Machinery Corporation, New
 York, N. Y., a corporation of Delaware

Application December 18, 1929
 Serial No. 414,846

23 Claims. (Cl. 12—36)

This invention relates to apparatus for use in the manufacture of footwear particularly by those processes in which the sole is adhesively attached to the lasted upper, and more particularly to sole-affixing machines of the multiple-press type.

A general object of the invention is to provide an apparatus by which soles may be adhesively affixed in a rapid, efficient and economical manner.

A particular object of the invention is to provide a sole-affixing machine of the multiple-press type which is of simple and sturdy construction and which operates with ease and efficiency, conserving the time and energy of the operator, whereby an increased number of soles may be affixed per unit of time and labor.

A more specific object of the invention is to provide a sole-affixing machine including a carrier and a plurality of shoe presses having inflatable pads and means for clamping a shoe thereagainst, having simple and novel means for intermittently advancing the press carrier and for insuring proper alignment of each press with a source of fluid pressure supply when the press passes said source.

Another object of the invention is to provide improvements in the construction of the sole-affixing press and the clamping mechanism thereof.

Other objects of the invention will in part be obvious and will in part appear hereinafter.

The invention accordingly comprises the features of construction, combination of elements and arrangement of parts which will be exemplified in the construction hereinafter set forth, and the scope of the application of which will be indicated in the claims.

For a fuller understanding of the nature and objects of the invention, reference should be had to the following detailed description taken in connection with the accompanying drawings, in which:

Fig. 1 is a plan view of a preferred embodiment of the invention, portions of the frame and associated parts being broken away for convenience of illustration;

Fig. 2 is a front elevation of Fig. 1, the right-hand end being shown in vertical longitudinal section;

Fig. 3 is a rear elevation of Fig. 1 partly broken away;

Fig. 4 is a transverse vertical sectional view taken along the broken line 4—4 in Fig. 1;

Fig. 5 is an end elevation of the right-hand end of Fig. 1;

Figs. 6, 7 and 8 are respectively plan, rear and side elevations of the fluid pressure supply source and associated mechanism;

Fig. 9 is a wiring diagram showing the circuit of the carrier driving mechanism;

Fig. 10 is a detail view partly in section of one of the shoe presses, together with associated parts of the carrier mechanism;

Fig. 11 is an elevation of the shoe press viewed from the right of Fig. 10;

Fig. 12 is a detail sectional view taken along the line 12—12 in Fig. 10;

Fig. 13 is a detail view of an operating mechanism for the safety switch; and,

Fig. 14 is a detail view, partly broken away, of the air supply chuck mechanism taken along the line 14—14 in Figure 6.

Considered generally, the present invention includes as novel features an improved type of carrier for sole-affixing presses, improvements in the presses per se, simple means for intermittently driving the carrier and stopping it when each of the presses has reached an approximate position of the traverse, means for aligning the fluid pressure supply source with the press at this time, means for rendering the carrier driving means again operative after the pad of the press has been inflated and all parts have returned to normal position, and means for assisting the operator in rapidly emptying and filling the presses with shoes.

Referring more particularly to the drawings, the embodiment shown comprises a pair of opposed elongated front and rear frame members 20 and 21, the bottom edges of which may rest suitably on the floor and the top edges of which stand to a height approximating the waist of the operator. These members are suitably connected at their ends by brace members 22 and form a space which may, if desired, be entirely enclosed as by means of sheet metal insets 23.

Mounted between the frame members and toward the ends thereof are a pair of transverse drums 24, one or both of which may be driven by a motor (not shown). These drums are of appropriate diameter to give sufficient driving power and to provide suitably spaced upper and lower traverses for a conveyor 25 which passes thereover. The conveyor may be of any suitable construction, but is preferably of the belt-type, and on its upper traverse is supported by a cross-piece 26 extending between the frame members 20 and 21 and located substantially on the upper horizon-

tal tangent of the drums 24. The cross-piece 26 thereby relieves the conveyor 25 from the weight of the presses on the upper traverse.

Secured to the belt-conveyor 25 at spaced intervals and extending transversely thereof is a series of cleat members 27 to which the shoe presses 28 are detachably secured as by means of hook members 29. The cleat members are preferably somewhat wider than the conveyor 25 and 10 the opposed frame members 20 and 21 are provided on a line slightly below the lower traverse of the conveyor with ledge members 30 on which the ends of the cleats 27 ride, thereby relieving the conveyor 25 of the weight of the presses on its 15 lower traverse.

The sole-affixing presses 28, as shown particularly in Figs. 10-12 inclusive, each comprises a hollow base member 31 having a depression 32 in its top generally conforming in longitudinal 20 contour to the bottom of a shoe to be clamped thereon. Disposed within the depression 32 is an inflatable pad 33 which is connected to an inlet valve having a nipple 34 and an outlet valve controlled by a plunger 35. Disposed over the pad 33 25 is a wear-plate 36 of leather or the like, which is clamped to the base member 31 at the ends by flange members 37. At the forward end of the press is an up-standing post 38 on which is pivot- 30 ed a clamping lever 39 which has its longer end extending rearwardly over the press and ending in a notch 40. This notch is normally engaged with a pin 41 passing through one of a series of holes 41' in a bail member 42, which is in turn pivoted to the rear of the base member 31 and 35 has a rearwardly extending arm 43, for a purpose hereinafter to be described.

The other end of the lever 39 extends outwardly at 44 a short distance from the post 38 and 40 preferably carries an anti-friction roller 45, for a purpose hereinafter to be described. Intermediate of the post 38 and the bail member 42, the clamping lever 39 is provided with a plurality of spaced notches 46 and 47 which are adapted to 45 accommodate pin members 48 and 49 of the in-step pad and last pin carrying members 50 and 51 respectively. These last mentioned members are similarly constructed in that they are provided with an elongated vertical slot 52 through 50 which the lever 39 passes and across the bottom of which the aforesaid pins 48 and 49 are disposed. At the top of the slot 52 there is provided a spring pressed plunger 53 which acts to force the clamping lever 39 downwardly with respect to the members 50 and 51 so that normally the pins 55 48 and 49 are in engagement respectively with one of the notches 46 and 47.

As is shown particularly in Fig. 4, the fluid pressure is supplied to the presses by means of a reciprocable chuck 54 which is connected by 60 means of a flexible tubular member 55 to a suitable source of pressure such as, for example, an air tank (not shown), the chuck being reciprocated through a system of levers 56 which connects with a foot treadle 57. The chuck 54 may be 65 conveniently constructed as is shown in Fig. 8 so that it is normally closed but is opened by the pressure of the nipple 34, whereby the pressure from the air tank may be transmitted to the pressure pad 33.

70 More particularly the chuck 54 may be of a usual type, having a valve pin 58 slidable within a bore 59 and having a head 60 and shoulder 60' normally seated and held against a rubber gasket 61 by the air pressure. The chuck also 75 is preferably provided with a conical head 62

which readily accepts the inlet nipple 34 of the shoe presses and in order to insure a proper seating the chuck is mounted for limited universal movement. As shown in Fig. 14, the chuck 54 is reciprocably supported in a head 63 by 80 means of a plurality of spring pressed pins 64 which are limited as to their inward movement by collars 65 so that the chuck is normally in centered position with respect to the head, but is movable to align with the nipple.

With a view to simplifying the construction of the carrier driving means and of eliminating the necessity of a highly accurate carrier stop mechanism, the chuck 54 and head 63 are mounted for limited movement along the path of the air inlet nipples of the shoe presses and are operatively connected with the driving mechanism in such a way that as each shoe press passes the zone of limited movement, the chuck and the air inlet nipple of the press are aligned and thereupon 90 the carrier is stopped. The inflating operation may then be accomplished and the movement of the carrier recommended.

A preferred form of accomplishing this action is shown in Figs. 6-8 inclusive, in which the head 100 63 is mounted upon a slide bar 66 which is held in brackets mounted upon the rear frame member 21 and which is normally retracted toward the side from which the presses approach by means of a spring 67. Mounted upon the parts associated with the slide bar 66 is a pivoted latch member 68 which normally lies within the path of a lug 69 attached to the front face of each of the shoe presses 28 whereby as the press reaches the zone of limited movement of the 110 chuck 54, the lug 69 engages the latch member 68 and moves the chuck 54 through the zone in alignment with the inlet nipple 34 of the press. In order ultimately to release the engagement between the latch member 68 and the lug 69 115 and to allow the press to continue along the traverse of the conveyor, a cam 70 is provided which gradually raises the latch 68 out of the path of the lug 69 and allows the slide bar 66 with the chuck 54 and associated parts to be returned 120 to their original position by the spring 67.

In order that there may be sufficient time for the operator to clamp the shoe in the press and inflate the pressure pad, it is desirable that the movement of the conveyor be interrupted while 125 the chuck 54 is in alignment with the nipple 34, and for this purpose there is provided a normally closed limit switch 71 having a pivoted arm 72 preferably carrying a roller 73 which is engaged and opened by the slide bar 66 as it is moved 130 by the lug 69 acting against the latch member 68 to a position slightly in advance of that shown in Fig. 6, whereupon the power for the conveyor driving motor is cut off and the conveyor comes to a drift stop. When the press has been loaded 135 and inflated, the operator pushes a start button 74 of a control switch 74' which is conveniently located as shown in Fig. 4, and which shunts the power past the limit switch 71 and again starts the motor, whereupon the lug 69 continues to move the slide bar 66 through the latch member 68 until released by the cam 70 and returned to original position, as above described, by the spring 67, and then the limit switch 71 automatically closes.

145 In order to insure safety in operation, the control switch 74' also has an emergency stop button 75, and the mechanism is provided with a second switch 76, which will be referred to as a "series safety switch", which may be conveniently 150

associated with the system of levers 56 so that unless the treadle 57 is in normal position and all parts are clear, the power circuit will be open and the conveyor will not start until such parts 5 are cleared.

A suitable mechanism for controlling the safety switch 76 is shown in Fig. 13 in which the system of levers 56 includes a bell crank lever 77 to which is affixed a cam 77' which operates to open 10 the switch 76 as soon as the treadle 57 is pressed downwardly and to hold the switch open until the treadle returns to normal position.

In Fig. 9 there is given a typical wiring diagram of a control circuit which is suitable for use in the mechanism above described with, for example, a single phase 110 volt current. The power comes into terminals L₁ and L₃, L₁ being connected with the terminal L₂ in the usual manner. When the normally open starting 20 switch 74 is closed, a pilot current flows from L₃ to the terminal *a* of the switch 74', through the switch to terminal *b*, through the series safety switch 76, when used, to the terminal *d*, or directly to the terminal *d*, as shown by the dotted 25 line, if the safety switch is not used. From *d* the current passes through the solenoid coil E of the relay and then to the terminal L₂, thus causing the sliding switch F to be moved against its 30 bias to the left to connect the terminals L₁ and *g*, L₃ and *h*, and the terminals *j* and *k* respectively, whereupon the main current flows from L₁ to *g* and thence through the motor M and back through *h* to L₃. At such time starting 35 switch 74 may be returned to its normally open position. The holding current which holds the switch F in closed position passes from the terminals L₂ through the relay E to the terminal *d*, thence to terminal *b* of the switch 74' through the terminal *c* to the limit switch 71, through terminals *j* and *k* of the switch F, and thence to the 40 terminal *h* and again through the switch F to the terminal L₃. Finally, as will be readily understood, as soon as the stop button 75 of the switch 74' is pressed and the contact between *b* and *c* is broken, or as soon as the limit switch 45 71 is opened, the holding current will be interrupted and the switch F will return to open position, whereupon the motor will stop.

Other features of the invention are shown particularly in Figs. 1-4 inclusive in which an air release cam 78 positioned in advance of the loading station releases the air from the presses automatically as they approach by pressing in the plunger 35; a cam 79, which forms a continuation of a guard member 80 acts on the projecting arm 43 of the bail member 42 to release the clamping lever 39; and a cam 81 acts on the rollers 45 as they pass to lift the clamping lever 39 away from the pad, thereby facilitating the 50 removal of the finished shoe. The cam 81 may be suitably formed from one or more leaf springs mounted upon intermediate supports 82 and having one of the free ends positioned above the loading station so that it is sufficiently resilient to allow the operator to press down the clamping lever 39 and secure it with the bail member 42 prior to inflating the pad. The guard member 80 passes around the traverse of the machine and serves to prevent entanglement of the bail 55 members 42 of any empty presses.

From the above description the principles of operation and the novel features of the present invention will be readily apparent to one skilled in the art. It will be understood that certain of 60 the features of the present invention may be

utilized in connection with various types of presses used in the manufacture and repair of footwear, as well as with various types of press carriers heretofore suggested for use in machines of the multiple-press type, and various 65 mechanisms for advancing the carrier. Therefore, it is for reasons of convenience and simplicity that the illustrated embodiment of the invention has been confined to a preferred type of carrier and carrier advancing means, and to the air pressure type of press. It is to be understood, however, that the invention is not limited to these features or to the use in sole-affixing machines as distinguished from sole-laying or sole-leveling machines, and since certain changes may 70 be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. In a machine of the class described, in combination, a movable carrier, a plurality of shoe presses mounted on said carrier and adapted to be moved through a circuitous path thereby, each of said presses including an inflatable pressure pad having an inlet valve and means for holding a shoe against said pad, a source of fluid pressure disposed adjacent said carrier, said source of fluid pressure being limitedly movable along the path of the presses, and means for aligning the inlet valve of each press with the said source of fluid pressure over at least a portion of the range of the limited movement thereof as the press passes.

2. In a machine of the class described, in combination, a movable carrier, a plurality of shoe presses mounted on said carrier and adapted to be moved through a circuitous path thereby, each of said presses including an inflatable pressure pad having an inlet valve and means for holding a shoe against said pad, a fluid pressure supply mechanism mounted adjacent said carrier and being limitedly movable along the path of the presses, means on each of said presses for contacting with a portion of said supply mechanism for aligning the mechanism with the inlet valve of the press over at least a portion of the range of limited movement as the press passes the said mechanism, and means for thereafter disengaging the aligning means.

3. In a machine of the class described, in combination, a movable carrier, a plurality of shoe presses mounted on said carrier and adapted to be moved through a circuitous path thereby, each of said presses including an inflatable pressure pad having an inlet valve and means for holding a shoe against said pad, means for driving said movable carrier, a fluid pressure supply mechanism mounted adjacent said carrier and being limitedly movable along the path of the presses, means on each of said presses for contacting with a portion of said supply mechanism for aligning the mechanism with the inlet valve of the press over at least a portion of the range of limited movement as the press passes the said mechanism.

- nism, means for rendering the carrier driving means inoperative during such alignment, means for thereafter disengaging the aligning means, and means for rendering said carrier driving means again operative to bring another press to aligned position. 80
4. In a machine of the class described, in combination, a conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply chuck disposed adjacent said conveyor and limit-edly movable along the path thereof, means on each of said presses for engaging and moving said chuck to align it with the inlet valve of the press, and means for thereupon moving said chuck into contact with said inlet valve to inflate the pad of the press. 85
5. In a machine of the class described, in combination, a conveyor, means for driving the conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply chuck mounted on a bar having limited sliding movement along the path of said conveyor adjacent the inlet valves of said presses, a lug on each of said presses, a pivoted latch member connected with said bar and positioned normally in the path of said lugs whereby as each press passes the vicinity of the chuck the chuck is aligned and moves along with said inlet valve, a limit switch operated by said sliding bar for opening the circuit of the conveyor driving means when the bar is moved as aforesaid, means for engaging the chuck with the inlet valve to inflate the pad and then to disengage the same, means for shunting the circuit of the electrical driving means past the opened limit switch, cam means for raising the pivoted latch out of engagement with the lug on the press, and means for thereafter returning the sliding bar and chuck to its original position whereby the said limit switch is again closed. 90
6. In a machine of the class described, in combination, a conveyor, electrical means for driving the conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply chuck mounted for limited movement along the path of said conveyor adjacent the inlet valves of said presses, means on each of said presses for engaging and moving said chuck to align it with said inlet valve as the press passes by the chuck, means for rendering inoperative the conveyor driving means at such time, means for engaging the chuck with the inlet valve to inflate the pad and then to disengage the same, and means for rendering the conveyor driving means again operative until the inlet valve of the next press is in aligned position with the chuck. 95
7. In a machine of the class described, in combination, a conveyor, means for driving the conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply chuck mounted for limited sliding movement along the path of said conveyor adjacent the inlet valves of said presses, means on each of said presses for engaging and moving said chuck to align it with said inlet valve as the press passes by the chuck, means actuated by the movement of said chuck for rendering inoperative the conveyor driving means at such time, means for engaging the chuck with the inlet valve to inflate the pad and then to disengage the same, and means for rendering the conveyor driving means again operative until the next press is in aligned position with the chuck. 100
8. In a machine of the class described, in combination, a conveyor, electrical means for driving the conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply chuck mounted adjacent the path of the inlet valves and limitedly movable therealong, co-operating means between said presses and said chuck aligning said chuck with the inlet valve of each press for a limited distance of its movement past the vicinity of the chuck, means for opening the circuit of the conveyor driving means at such time, treadle operated means for then engaging the chuck with the inlet valve to inflate the pad, means for returning the treadle toward its normal position to disengage the chuck from the valve, means for shunting the circuit of the conveyor driving means past the aforesaid opening in the circuit, and a safety switch in said circuit which is closed when the treadle is in its normal position and is open when the treadle is depressed so that the chuck is not clear of the path of the inlet valve. 105
10. In a machine of the class described, in combination, a conveyor, electrical means for driving the conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply chuck mounted on a bar having limited sliding movement along the path of said conveyor adjacent the inlet valves of said presses, a lug on each of said presses, a pivoted latch member 110

- connected with said bar and positioned normally in the path of said lugs whereby as each press passes the vicinity of the chuck the chuck is aligned and moves along with said inlet valve, 5 a limit switch operated by said sliding bar for opening the circuit of the conveyor driving means when the bar is moved as aforesaid, treadle operated means for engaging the chuck with the inlet valve to inflate the pad and then to disengage the same, means for shunting the circuit of the electrical driving means past the opened limit switch, cam means for raising the pivoted latch out of engagement with the lug on the press, and means for thereafter returning the 10 sliding bar and chuck to its original position whereby the said limit switch is again closed. 15 11. In a machine of the class described, in combination, a conveyor, electrical means for driving the conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply 20 chuck mounted on a bar having limited sliding movement along the path of said conveyor adjacent the inlet valves of said presses, a lug on each of said presses, a pivoted latch member connected with said bar and positioned normally 25 in the path of said lugs whereby as each press passes the vicinity of the chuck the chuck is aligned and moves along with said inlet valve, a limit switch operated by said sliding bar to open the circuit of the conveyor driving means when the bar is moved as aforesaid, treadle operated means for engaging the chuck with the inlet valve to inflate the pad and then to disengage the same, switch means for shunting the circuit of the electrical driving means past the 30 opened limit switch, cam means for raising the pivoted latch out of engagement with the lug on the press, means for thereafter returning the sliding bar and chuck to its original position whereby the said limit switch is again closed, and 35 a safety switch in said driving circuit operated by said treadle which is closed when the treadle is in its normal position and is opened when the treadle is depressed. 40 12. In a machine of the class described, in combination, a conveyor, electrical means for driving the conveyor, a plurality of shoe presses mounted on said conveyor and adapted to be moved through a circuitous path thereby, each of said presses including an inflatable pressure pad having an inlet valve and means for clamping a shoe against said pad, a fluid pressure supply 45 chuck mounted on a bar having limited sliding movement along the path of said conveyor adjacent the inlet valves of said presses, a lug on each of said presses, a pivoted latch member connected with said bar and positioned normally 50 in the path of said lugs whereby as each press passes the vicinity of the chuck the chuck is aligned and moves along with said inlet valve, a limit switch operated by said sliding bar to open the circuit of the conveyor driving means when the bar is moved as aforesaid, treadle operated means for engaging the chuck with the inlet valve to inflate the pad and then to disengage the same, switch means for shunting the circuit of the electrical driving means past the 55 opened limit switch, cam means for raising the pivoted latch out of engagement with the lug on the press, means for thereafter returning the sliding bar and chuck to its original position whereby the said limit switch is again closed, and 60 a safety switch in said driving circuit operated by said treadle which is closed when the treadle is in its normal position and is opened when the treadle is depressed. 65 13. In a machine of the class described, in combination, a movable carrier, a plurality of shoe presses mounted on said carrier and adapted to be moved through a circuitous path thereby, each of said presses including a pad, a pivoted lever for clamping a shoe against said pad, a loading station for said presses located at a predetermined position in said circuitous path, and a cam member located adjacent said path at a position preceding said loading station, each of said pivoted levers extending past the pivot and providing an extension which contacts with said cam as the press passes therewith to raise the clamping end of the pivoted lever away from said pad, said cam member having a yieldable portion extending over said loading station to engage and hold said clamping lever in raised position while at such station. 70 14. In a machine of the class described, in combination, a movable carrier, a plurality of shoe presses mounted on said carrier and adapted to be moved through a circuitous path thereby, each of said presses including a pad and means for clamping a shoe against said pad, means for moving said carrier, means successively controllable by each of said presses for intermittently bringing said carrier to a drift stop as each press approaches a limited zone of its path of movement, and means in said zone for increasing the pressure of the pad against the shoe. 75 15. In a machine of the class described, in combination, a movable conveyor including an inflatable pad having an inlet valve, a plurality of shoe presses mounted on said conveyor and adapted to be moved through a circuitous path thereby, each of said presses including a pad and means for clamping a shoe against said pad, means for moving said conveyor, means for intermittently bringing said conveyor to a drift stop as each press approaches a limited zone of its path of movement, a fluid pressure supply source located at said zone, means for aligning the inlet valve of the press with said fluid pressure supply source, and means for moving the inlet valve and fluid supply source into cooperative engagement to inflate the pad prior to the next movement of the conveyor. 80 16. In a machine of the class described, in combination, a flexible conveyor, a plurality of shoe presses mounted on said conveyor and adapted to be moved through a circuitous path thereby, each of said presses including a pad, a pivoted lever for clamping a shoe against said pad, means for releasably holding said pivoted lever in clamping position, a loading station for said presses located at a predetermined position in said circuitous path, and a plurality of cam members located adjacent said path at positions preceding said loading station, one of said cam members acting against the pivoted lever securing means to release the lever, said cam forming a continuation of a guard member disposed around one end of the conveyor and serving to prevent said securing means from becoming entangled if and when an empty jack passes around the circuitous path, each of said pivoted levers extending past the pivot and providing an extension which contacts with another of said cams as the press passes therewith to raise the clamping end of the pivoted lever away from said pad, the extending end of 85 90 95 100 105 110 115 120 125 130 135 140 145 150

- the pivoted lever being provided with an anti-friction roller which contacts with the second-mentioned cam.
17. In a machine of the class described, in combination, a movable carrier, a plurality of shoe presses mounted on said carrier and adapted to be moved through a circuitous path thereby, each of said presses including a pad, a pivoted lever for clamping a shoe against said pad, means for releasably holding said clamping lever in clamping position, a loading station for said presses located at a predetermined position in said circuitous path, and a plurality of cam members located adjacent said path at positions preceding said loading station, one of said cam members acting against said clamping lever securing means to release the clamping lever, each of said pivoted levers extending past the pivot and providing an extension which contacts with another of said cams as the press passes therewith to raise the clamping end of the pivoted lever away from said pad.
18. In a machine of the class described, in combination, a movable carrier, a plurality of shoe presses mounted on said carrier and adapted to be moved through a circuitous path thereby, each of said presses including a pad, a pivoted lever for clamping a shoe against said pad, means for releasably holding said pivoted lever in clamping position, a loading station for said presses located at a predetermined position in said circuitous path, and a plurality of cam members located adjacent said path at positions preceding said loading station, one of said cam members acting against the pivoted lever securing means to release the lever, each of said pivoted levers extending past the pivot and providing an extension which contacts with another of said cams as the press passes therewith to raise the clamping end of the pivoted lever away from said pad, said last-mentioned cam member being formed of leaf springs having a resilient end whereby as the raised clamping lever rests under such end it may be forced downwardly into clamping position.
19. A clamping mechanism for a shoe press adapted for adhesively affixing an outer sole to a lasted shoe upper, including, in combination, a pivoted lever having a substantially flat upper edge and spaced notches on its lower edge, a last pin and instep pad supporting members disposed on said pivoted lever and each having an elongated slot through which said lever passes, a pin fixed transversely in said slot at the lower end thereof and adapted to co-act with said notches, and a spring pressed plunger disposed at the top of the slot and operating longitudinally of the member to press against the flat upper edge of the pivoted lever whereby the transverse pin is urged into and held in one of the notches.
20. In a shoe-making machine of the class described, in combination, a movable conveyor, a shoe press on said conveyor, retractable pressure means cooperating with said press and adapted to project into the path of the same, a treadle adapted to retract said pressure means, an electric motor for driving the conveyor, circuit control means for said motor including a conveyor operated switch, a switch operated by said
- treadle, and a manually operable start switch, said start switch being operable to shunt the current past said conveyor operated switch when the latter is open, said treadle operated switch being in series with each of the other switches whereby the circuit cannot be closed unless said pressure means is retracted from the path of said press.
21. In a shoe-making machine of the class described, in combination, a movable conveyor, a shoe press on said conveyor, retractable pressure means cooperating with said press and adapted to project into the path of the same, a treadle adapted to retract said pressure means, an electric motor for driving the conveyor, circuit control means for said motor including a conveyor operated switch, a switch operated by said treadle, a manually operable start switch, said start switch being operable to shunt the current past said conveyor operated switch when the latter is open, said treadle operated switch being in series with each of the other switches whereby the circuit cannot be closed unless said pressure means is retracted from the path of said press, means for closing said conveyor operated switch shortly after the circuit is temporarily closed by said start switch, and means for thereafter opening said conveyor operated switch to stop the conveyor.
22. In a shoe-making machine of the class described, in combination, a movable conveyor, a shoe press on said conveyor, retractable pressure means cooperating with said press and adapted to project into the path of the same, a treadle adapted to retract said pressure means, an electric motor for driving the conveyor, circuit control means for said motor including a conveyor operated switch, a switch operated by said treadle, manually operable start and stop switches, said start switch being operable to shunt the current past said conveyor operated switch when the latter is open, said treadle operated switch being in series with each of the other switches whereby the circuit cannot be closed unless said pressure means is retracted from the path of said press, means for closing said conveyor operated switch shortly after the circuit is temporarily closed by said start switch, and means for thereafter opening said conveyor operated switch to stop the conveyor, said stop switch being normally closed and operable at any time to open the circuit and stop the conveyor at the will of the operator.
23. In a machine of the class described, in combination, a carrier, a plurality of shoe presses mounted on said carrier and adapted to be moved through a circuitous path thereby, each of said presses having an inflatable pad having an inlet valve and means for clamping a shoe against said pad, a fluid pressure supply mechanism mounted adjacent said carrier, and means for aligning said inlet valve of each press in turn with said fluid supply mechanism; said fluid supply mechanism including a reciprocable chuck mounted for limited universal movement and having a conical mouth adapted to receive said inlet valve.

ARTHUR J. WEISS.
